UNITED STATES PATENT OFFICE.

ALFRED HOPKINS, OF BOSTON, MASSACHUSETTS.

CURTAIN-STRETCHER.

1,328,995.

Specification of Letters Patent. Patented Jan. 27, 1920.

Application filed June 17, 1919. Serial No. 304,882.

To all whom it may concern:

Be it known that I, ALFRED HOPKINS, a citizen of the United States, residing at Boston, in the county of Suffolk and State 5 of Massachusetts, have invented new and useful Improvements in Curtain-Stretchers, of which the following is a specification.

This invention relates to an adjustable portable frame, on which a lace or other curtain may be stretched after washing, and held in a flat position while being dried, the frame being movable into a drying-room after the curtain has been adjusted upon it.

The invention has for its object to provide 15 a curtain stretcher which is adjustable, so that it is adapted to hold curtains of various sizes in a stretched and flat condition, while being dried.

The invention consists in the improvements 20 which I will now proceed to describe and claim.

Of the accompanying drawings forming a part of this specification,—

Figure 1 is a side view of a curtain 25 stretcher embodying the invention, the stretcher being supported by an overhead track.

Fig. 2 is a perspective view of the same.

Fig. 3 is a side view showing partly in 30 section, and partly in elevation, portions of the stretcher and track.

Fig. 4 is a section on line 4—4 of Fig. 3, looking toward the left.

Fig. 5 is a fragmentary sectional view, 35 showing a portion of the top member of the frame, and a portion of the vertical adjustable bar hereinafter described.

Fig. 6 is a section on line 6—6 of Fig. 5, looking toward the right.

Fig. 7 is a fragmentary perspective view, 40 illustrating a portion of the means for raising and lowering the horizontal bar.

The same reference characters indicate the same parts in all of the figures.

My improved curtain stretcher includes a 45 rectangular portable frame composed of a horizontal top member 12, a horizontal bottom member 13, and vertical end members 14 and 15, said members being rigidly connected and forming a rectangular, oblong frame.

The frame is provided with suitable curtain-engaging means, here shown as embodied in strips 16 of card clothing, attached to the top member 12, and to the end 50 members 14 and 15, the material called card

clothing being composed of a sheet or strip of leather, or the like, and wire teeth closely assembled on the strip, the points of the teeth projecting from one side of the strip, and being adapted to engage the meshes of a lace curtain.

The frame may be suspended from a fixed horizontal trolley track 18, by means of hangers 19, attached to the top member 12, and trolleys 20, connected with said hangers, 65 and adapted to run on the track. The track may be extended into a drying-room, the length of the track being such that the frame will be supported outside the drying-room while the curtain is being applied thereto, 70 and then moved into the drying-room.

To the under side of the top member 12 of the frame is attached a trolley track 21, preferably composed of sheet metal, formed to provide two track portions for trolleys 22, 75 connected as hereinafter described, with a vertical cross-bar 23.

The cross-bar 23 is formed to extend from the top member 12 to the bottom member 13 of the frame, and is provided with curtain-engaging means, preferably embodied in a strip 16^a of card clothing, suitably attached to the cross-bar. The trolleys 22, of which four pairs are preferably employed, are connected with the bar 23 by hangers 26 and 27, 80 extending through a longitudinal slot in the under side of the track 21. The hanger 26 is attached to the upper end of the cross-bar 23 and is connected with two pairs of wheels 22, as shown by Figs. 5 and 6. The hanger 27 is angular and attached to one side of the bar 23, and is connected with two pairs of wheels 22, the arrangement being such that the wheels are arranged in tandem order, and provide an elongated wheel base where- 90 by the bar 23 is maintained in a vertical position and prevented from tipping or oscillating.

30 represents a horizontal cross-bar formed to extend practically the entire distance between the end members 14 and 15 of the frame, said horizontal bar being vertically movable in an elongated slot 31 in the vertical cross-bar 23, the sides of said slot forming guides for the cross-bar 30. The 100 end portions of the cross-bar 30 are provided with spring-pressed bolts 32, adapted to engage sockets 33 on the end members 14 and 15, the sockets being arranged in vertical rows, so that the cross-bar 30 may be located 110

at various heights. The bolts 32 may be connected by a cord 34 running through guides on the bar 30, and enabling the operator to simultaneously retract the bolts and thus 5 unlock the cross-bar.

I have provided means for raising and lowering the horizontal cross-bar 30 and maintaining it in a horizontal position, said means including flexible cords 36 and 37 attached to opposite ends of the bar 30, and cord guides which are preferably pulleys 38 journaled in bearings on the top member 12. The cord 37 passes over two guides 38 at 10 opposite end portions of the frame, and the cord 36 extends over one of the guides 38, and over an intermediate guide 38^a (Fig. 7), the two cords meeting at 38^b, so that they 15 may be simultaneously manipulated by an operator at one end of the frame. A counterbalancing weight 40 is attached to the cord and is adapted to yieldingly hold the cross-bar 30 at any position to which it may be vertically adjusted, the object of the weight being to prevent the cross-bar from 20 dropping loosely to the bottom of the frame, and to hold it in convenient position to be locked at the desired height. The cross-bar 30 is provided with curtain-engaging means, 25 preferably embodied in a strip 16^b of card clothing.

It will now be seen that the adjustable cross-bars 23 and 30 are adapted to coöperate with a portion of the top member 12, and a portion of either of the end members 14 and 15, in forming a frame of the size of 30 the curtain to be dried. The operator, after 35 suitably adjusting the cross-bars, engages the edges of the curtain with the card clothing on the frame members and on the cross-bars, and then moves the frame into the 40 drying-room.

As indicated by Fig. 6, the frame and the cross-bars are provided with curtain-engaging means at opposite sides, so that two curtains 45 may be simultaneously stretched and dried, one on each side of the frame. The card clothing strips 16^a on the vertical cross-bar are preferably elongated, as shown by Fig. 6, so that they overlap the sides of the

track 21, and substantially meet the strips 50 16 on the top member 12.

The vertical cross-bar 23 is forked at its lower end to bestride the bottom member 13 of the frame, the fork being conveniently formed by a slot 23^a in the lower end of the 55 cross-bar.

I claim:

1. A curtain stretcher comprising a rectangular portable frame composed of rigidly connected top, bottom and end members, 60 provided with curtain-engaging means, a trolley track attached to the top member, a longitudinally slotted vertical cross-bar having curtain-engaging means, trolleys connected with the upper end of said bar adapted to run on said track, the lower end of the cross-bar being forked to bestride and slide upon the bottom frame-bar, a horizontal cross-bar having curtain-engaging means and slidably vertically in the slot of the vertical cross-bar, coöoperating locking members 65 on the horizontal bar and on the frame-end members, whereby the horizontal bar may be locked to the frame in different positions, and means for raising and lowering the horizontal bar, said means including cords attached to opposite ends of the horizontal bar, and cord guides on the top frame-bar, said cords being operable from one end of the frame to move the horizontal bar vertically 70 and maintain the latter in a horizontal position.

2. A curtain stretcher substantially as specified by claim 1, the said trolleys being arranged to provide an elongated wheel base 85. maintaining the vertical bar in an upright position.

3. A curtain stretcher substantially as specified by claim 1, the said cords being provided with a weight adapted to counter-balance the horizontal bar.

4. A curtain stretcher substantially as specified by claim 1, the curtain-engaging means on the vertical bar being extended to overlap the said track.

In testimony whereof I have affixed my signature.

ALFRED HOPKINS.
